[57] CLAIM

The ornamental design for a lawn mower housing or the like, as shown and described.

DESCRIPTION

FIG. 1 is a perspective view of a lawn mower housing or the like, showing our new design;

FIG. 2 is a rear elevational view thereof;

FIG. 3 is a bottom plan view thereof;

FIG. 4 is a left side elevational view thereof.

The right side elevational view of our new design is a mirror image of the left side elevational view shown in FIG. 4.

Broken lines depicting the wheels and the front wheel assembly are for illustrative purposes only and form no part of the claimed design.
